BLANK FEEDER AND EJECTOR

William Ward Davidson, Evanston, Ill.

Application September 30, 1935, Serial No. 42,876

14 Claims. (Cl. 271—4)

This invention relates to improvements in sheet feeding mechanisms for printing presses, and has special reference to such devices arranged and adapted to successively feed individual sheets, envelopes or cards from a stack of blanks to printing position and after the impression has been made thereon to remove the fed articles and arrange them in a stack.

The invention has special reference to feeding devices of the character referred to particularly arranged and adapted for use in connection with automatic printing machines such as the "Addressograph".

The "Addressograph" and similar machines are designed to print from successive plates carrying a series of addresses and to print or impress the addresses which are on the successive plates upon a similar series of envelopes, letter-heads, etc. At each operation of the press, one article is printed and the plate which carries the address is removed from printing position and the successive plate is moved into printing position.

My invention has to do with providing a feeding mechanism so related to the press that it will operate automatically in relation thereto to remove the printed article and feed another blank into printing position while the press is operating to remove the used plate and place the successive plate in printing position.

The improved feeding mechanism derives its power from the printing press operating parts and the connection is arranged and adapted to automatically operate the feeding mechanism in synchronism with the printing machine.

In carrying out my invention I arrange a movable member, which may be a tape or a slide, and I move this member in one direction to feed the blank into printing position in proper timed relation, I then move it in the opposite direction to move the printed article out of printing position.

To the accomplishment of the above and other objects and advantages, the invention consists in the means hereinafter fully disclosed and particularly pointed out in the appended claims, the accompanying drawings, forming part of this specification, and the following description setting forth, in detail a preferred embodiment of the invention and two modifications thereof, such disclosed arrangements, however, constituting merely illustrations of the various applications of the principle of the invention, which will readily suggest themselves to one skilled in the art.

The invention will be more readily understood by reference to said drawings, in which:—

Fig. 1 is a fragmentary side elevation of a mechanism embodying the invention in a preferred form and shown in connection of some of the typical associated parts of an "Addressograph" machine; 5

Fig. 2 is a top plan view of the mechanism shown in Fig. 1;

Fig. 3 is a fragmentary vertical longitudinal section on the line 3—3 of Fig. 2;

Fig. 4 is a fragmentary, transverse, vertical section on the line 4—4 of Fig. 2;

Fig. 5 is a fragmentary plan view, similar to Fig. 2, but showing a slight modification of the invention;

Fig. 6 is a fragmentary side elevation of the mechanism shown in Fig. 5;

Fig. 7 is an enlarged, fragmentary, elevational view of the tape driving mechanism shown in Fig. 6;

Fig. 8 is an enlarged fragmentary elevational view of the driving mechanism shown in Fig. 7, the view being similar to that shown in Fig. 6;

Fig. 9 is a detail horizontal section on the line 9—9 of Fig. 6;

Fig. 10 is a detail vertical section on the line 10—10 of Fig. 5;

Fig. 11 is a fragmentary top plan view showing a second modification of the invention;

Fig. 12 is a fragmentary, vertical, longitudinal section on the line 12—12 of Fig. 11; and 30

Fig. 13 is an end elevational view of the mechanism shown in Fig. 11, the plates being shown in section.

I will first describe the form of the invention shown in Figs. 1 to 4 inclusive. 35

In said figures 20 illustrates the frame of an "Addressograph" machine having a top plate 21. Projecting up through a suitable opening in the top plate is a head 22 which is mounted on a horizontal shaft 23, arranged below the plate 21. 40

The head is secured upon the shaft 23, which is mounted in suitable bearings indicated at 24 and is oscillated back and forth through suitable mechanism which connects a lower part of the head with a source of power such as an electric motor 25 mounted on the frame of the machine. 45

The head 22 projects forward as shown in Fig. 1 and has a depending impression part 27 at its forward end which is arranged above an opening 28 in the top plate 21. The printing machine is provided with suitable mechanism operated in time with the up and down movements of the impression head 27 and adapted to move a printing plate from a suitable stack, indicated at 29, arranged at the rear of the machine to a print- 50

55

ing position below the opening 28 and after the impression has been made to remove the used plate and place a successive plate in printing position. An inked tape, not shown, is arranged 5 to lie on top of the printing plate and beneath the head 27.

The feeding mechanism is arranged to feed articles, such as envelopes, indicated at 26 where they are supported in a stack in a guide trough 10 30 to a position between the impression head 27 and the printing plate below same and above the printing tape, and to remove the printed article from such position to a receptacle arranged below the holder 30 as indicated at 31, in which 15 the printed articles are stored in a stack as shown.

Power is supplied to operate the printing machine from any suitable source such as an electric motor 25 mounted on the frame of the machine and connected through suitable speed reducing mechanism indicated at 33 to a depending arm 34 rigid with the head 22. Power to operate the feeder is derived from the same source partly through the shaft 23 upon which the head 22 20 is mounted, and partly through the speed reducing means indicated at 33. The feeding mechanism for timing the movement of the articles into and out of printing position in synchronism with the up and down movements of the head 22 derives its power through the shaft 23.

At the foot or delivery end of the inclined guide 30 I arrange a separator roll 35 secured upon a horizontal shaft 36 carried at its ends in the free ends of arms 37 of bell-cranks 38 pivotally mounted on rigid side frame parts 39 at 40. The shaft 36 is mounted to rotate in bearings carried by the bell-cranks 38 and as the bearings are rather widely separated I provide a support 41 near the middle of the shaft 36 and adjacent to one end of the separator roll 35 and connecting the shaft 36 with a transverse rod 42 mounted in the ends of the other arms of the bell-cranks 38. The shaft 36 is connected at one end through a suitable ratchet clutch 43 with a toothed pinion 44 mounted to turn freely on the shaft 36. When the pinion 44 is rotated in a direction to cause the separator roll 35 to draw an envelope from the front of the stack and start it in its movement toward its printing position, the clutch operates to rotate the shaft 36 and with it the separator roll 35, but when the pinion 44 is rotated in the opposite direction the ratchet clutch 43 permits the shaft 36 to stand still.

55 The inclined trough 30 is carried on support bars 45 pivotally mounted at their lower forward ends on the framed parts 39 at 46. The rear ends of the support bars 45 are supported by braces 47. The upper ends of the braces 47 are 60 pivotally connected to the rear ends of the supports 45 by a transversely extending shaft 48 and their lower ends are adjustably secured to the rear ends of side bars which extend rearwardly from the frame of the printing machine 65 being bolted upon the top plate 21 by screws 49. The inclined trough 30 is carried by the shaft 48 on suitable blocks 50 carried by the shaft and the lower ends of the braces 47 are slotted as shown at 51 so that the feed trough can be adjusted as to inclination to suit the articles being fed.

70 For preventing the envelope which is being separated from the stack by the separator roll 35 dragging forward the next envelope in succession, there is provided a stationary abutment in

the form of a roller 52 below the separator roll 35 and spaced from the roller 35 just sufficient to allow one envelope at a time to pass. The roller 52 is carried on a shaft 52' and is held against rotation thereon. The separator roll 35 and the roller 52 constitute a caliper means for controlling the feed of the articles such as envelopes from the stack 26.

As this separating mechanism per se, is not a part of the present invention, it is not thought necessary to describe it more specifically except to say that the caliper means is pivotally mounted to swing up and down slightly and is counterbalanced by a weight 53 adjustably mounted on an arm 54 rigidly mounted on one 15 of the bell-cranks 38.

The envelopes to be printed when placed in the inclined trough 30, slide down same towards the caliper rolls 35 and 52 and the lower end of the forward envelope contacts with the feed roll 20 35 and when the same is rotated to feed the envelope the lower end of the envelope enters in between the rolls 35 and 52 and is fed forward toward the printing machine.

For intermittently rotating the separator roll 25 35 to separate and advance the envelopes in time with the printing operations, a horizontally arranged toothed rack 54' is provided, arranged to mesh with the teeth of the pinion 44 and turn same back and forth. Due to the ratchet clutch 43 the roll 35 is only rotated in the feeding direction. The rear end of the rack 54' is pivotally connected to the upper end of an arm 55 of a bell-crank 56 which is pivotally mounted at its elbow on the frame at 57. The free end 35 of the other arm 58 of the bell-crank is pivotally connected at 59 to the upper end of a depending link 60. The lower end of the link 60 is pivotally connected to the outer end of a rigid projection 61 extending out from a crank arm 62. The 40 crank arm 62 is rigidly mounted on the shaft 23 upon which the impression head 22 is also rigidly mounted and as it projects in the opposite direction to the head 22 from the shaft 23, its free end rises as the head 27 descends and vice-versa.

As the head 27 is moved down toward printing position, the projection 61 on the crank arm swings up as indicated by the arrow 63 on Fig. 4 and the rack is moved to the left as shown on Fig. 3, through the link 60 and bell-crank 56 and causes an envelope to be separated from the stack 26 and advanced.

The bottom guides 65 of the holder 30 are slightly curved up at their lower ends just beyond the separator roll 35 to direct the forward edges of the envelopes upon the upper side of a conveyor or pull-out roll 66. The conveyor roll 66 is rigidly mounted on a transverse shaft 67 which is rotatably mounted in bearings carried 60 by the frame parts 39.

Above the shaft 67 is a second transverse shaft 68 which carries idle rollers 69 adapted to be pressed toward the conveyor roll 66 to cause same to feed the envelopes forward. The shaft 68 is 65 carried at its ends in the free ends of arms 70 which are mounted at their opposite ends on a transverse shaft 71 so that they can swing up and down and they are yieldingly held down towards the conveyor roll 66 by a tension spring 72 70 connected between one of the arms 70 and the adjacent frame part 39.

The conveyor roll 66 is adapted to be continuously rotated to feed the envelopes delivered intermittently by the separator roll 35.

This continuous rotation of the conveyor roll 66 is accomplished as shown in the drawings, by a round belt or drive 73 which is trained around a grooved belt pulley 74 rigidly mounted on the conveyor roll shaft 67 and also around a grooved belt pulley 75 rigidly mounted on an intermediate shaft 76 arranged below the machine top 21 and connected by a driving belt 76' and shaft 77 with the belt 33 (see Fig. 1).

10 Suitable guide pulleys 78 and 79 are provided for guiding the belt 73 from the pulley 74 to the pulley 75.

In order to complete the feeding of the envelope after it leaves the conveyor roll 66, I provide, as shown in Figs. 1 to 4, inclusive, a tape or flat belt 80 which is arranged immediately above the top plate 21 and in substantial contact therewith and extends across the opening 28 in the top plate 21 and as close to the head 27 as is practicable. This feed tape has an intermittent motion to the right (Fig. 2), to feed the envelope into printing position and toward the left to discharge it after it has been printed.

This feed tape or belt, as shown, is a continuous belt and the two stretches 81 and 82 lie one on top of the other on the top of the top plate 21 as best shown in Fig. 3. The belt passes around a belt guide 83 at the right hand end of the printing machine (see Fig. 1) and both stretches 30 are guided downwardly at the opposite end of the machine around idle guide pulleys 84 and 85, mounted on supports projecting from the top plate 21, and is trained around a relatively large belt pulley 86 mounted on a shaft 87 which in turn is mounted in bearings on the free ends of arms 88 rigid with the machine frame.

The belt guide 83 has two small guide rollers 89 and 90 close to the top 21 and a third larger guide pulley 91 above the other two and is adapted to guide the two stretches of the tape close down to the top 21, (see Fig. 1).

The tape 80 is moved intermittently back and forth and for this purpose it is secured at one point to the periphery of the large pulley 86 by a screw 92 (see Fig. 3). The pulley is oscillated through approximately one-half of a revolution to move the tape 80 back and forth, and in time with the feeding of the envelopes by the separator roller 35, by means of a segmental gear 93 mounted to swing back and forth on a horizontal shaft 94 carried in brackets 95 projecting rigidly from the frame of the machine. The gear has a rigid arm 96 projecting in the opposite direction and the free end of the arm is connected by a link 97 with the crank arm 62. The segmental gear meshes with a pinion 98 mounted concentric with the belt pulley 86 and secured to the pulley to cause the pulley to rotate back and forth with the pinion. The movement of the gear 93 is sufficient to cause the pulley to rotate back and forth about one half of a revolution and to move the belt 80 back and forth sufficiently for the purpose.

The arrangement is such that as the envelope is fed by the separator roll 35 as has been described as the head 22 moves down towards the printing position, that is as the projection 61 is swung up, the segmental gear 93 is swung from its position as shown in Fig. 3 to its opposite position, thus rotating the belt pulley clockwise, (see Fig. 3), and the top or upper stretch of the tape is moved to the right (see Fig. 3) thus carrying the fed envelope, as it is delivered from the conveyor rolls 66 and 69, into the printing position.

75 In order that the envelope as it is carried into

printing position will not be lifted above its true level, an idle guide roll 99 is rotatably mounted above the tape on a vertically swinging support 100 pivotally mounted at its opposite end in a block 101 adjustably mounted on a stop rod 102. 5 The roll is arranged about the middle of the length of the head 27 and the stop rod extends toward the right hand end of the machine where it is adjustably secured to a support rod 103. The support 100 is pivotally mounted in the block 10 101 and is free to swing up and down and is pressed against the tape 80 or the envelope which may be in printing position by a spring 190.

At its free end the stop rod carries a vertical stop plate 104 against which the forward end of 15 the envelope contacts to properly register with the printing plate. As the rod 102 is longitudinally adjustable the stop 104 can be adjusted to properly register the articles being printed.

The support 103 is rigidly mounted on the top 20 plate of the machine by means of rigid brackets 105. Side guides 106 and 107 for the article being fed, are provided. These guides each have a flat bottom flange 108 and a vertically disposed flange 109 at its outer edge. The side guide 106 which 25 is at the front of the machine is rigidly carried by one end of support rod 110 which is adjustably carried at its other end on the support rod 103, and the side guide 107 which is at the rear of the machine is similarly carried by a support 30 rod 111, which is likewise adjustably mounted on the support rod 103. These guides can be adjusted from and toward each other to cause the article to be printed, as it is fed in between them, to be properly placed in printing position. As 35 shown in Fig. 2, the receiving ends of the guides 106 and 107 are slightly flared as shown at 112, so as to avoid any engagement with the advancing end of the article being fed in.

In order to time the placement of the article 40 to be printed accurately with the operation of the impression mechanism of the printing machine, the pressure roll 69 is lifted free of the conveyor roll 66 to permit the forward end of the envelope to freely project over same and at just the 45 right instant the pressure roll 69 is brought down upon the envelope causing it to be projected forward upon the conveyor tape 80.

To accomplish the described action of the pressure roll 69 a vertically arranged, pivotally mounted cam plate 113 is provided which is pivoted at its lower end at 114 to the adjacent frame part 39 and its upper end 115 is connected by a rod 116 to a projection 117 on the upper end of the arm 55 of the bell-crank 56. The rear 55 or free end 118 of the connecting rod 116 is threaded and I provide two adjustable stops 119 and 120 on the rod between which the projection 117 is received. These stops each consist of a pair of jamb nuts and I space the two pairs 60 apart to provide some lost motion between the projection 117 and the stops to properly time the operation of the pressure roll 69 to let the forward edge of the fed article enter freely between the feed roll and the pressure roll and 65 then be engaged by the rolls to convey it forward.

The cam plate 113 has a rounded cam projection 121 arranged to be swung beneath a roller 122 on the conveyor roll shaft 68 and lift 70 same against the force of the hold-down springs 72. Adjacent to the cam projection 121 the cam plate 113 is provided with a depression 123 into which the roller 122 is forced by the pull of the spring 72 and the pressure roll 69 is thus free 75

to be drawn down toward the conveyor roll 66 to engage the article being fed. The cam plate 113 is free to be swung forward to permit this engagement due to the lost motion between the 5 rod 116 and the projection 117.

The toothed rack 54' is guided and held down in engagement with the pinion 44 by means of a stationary guide 124 arranged above the rack.

The operation of the mechanism described is 10 as follows:

As the impression head begins to descend to make an impression, the separator roll 35 is rotated counter-clockwise to separate an envelope from the stack 26, the pressure roll 69 is first 15 lifted to let the forward end of the envelope enter between the two rolls 66 and 69 and then the roll 69 is pressed down to press the envelope against the conveyor roll 66 which is always rotating. At the same time the top stretch 81 of the feed 20 tape is moving to the right and as it receives the envelope from the rolls 66 and 69 it carries it forward in between the guides 106 and 107 and against the stop 104 into printing position.

After the envelope has been printed, the head 25 22 begins to rise and the top stretch 81 of the tape 80 is drawn to the left and carries the printed envelope to the left from the printing position and beneath the roll 66 to be discharged. A second pressure roll 125 is arranged below the pressure 30 roll 66 and the tape passes through between these rolls carrying the printed envelope with it. At the top of the receptacle 31 a deflector plate 126 is arranged to guide the envelope, being discharged, as shown at 127, down into the receptacle 31.

Carried on the head 27 are impression rolls 128 and 129 which are arranged to be passed back and forth beneath the head 27 when it is depressed into printing position and thus cause the 40 printing tape, not shown, to make the impression on the envelope in the usual manner from the printing plate not shown, but positioned in printing position below the opening 28 in the top plate 21.

45 The form of the invention shown in Figs. 5 to 10, inclusive, is similar to the form already described except that instead of the continuous feed tape 80 I provide a feed tape 130 which is attached at one end to the periphery of a large belt pulley 131 similar to the belt pulley 86 already described, and at its opposite end the tape 130 is mounted on a take-up device 132, located at the right hand end of the machine top 21. The take-up device is similar to a spring action shade 50 roller and properly tensions the tape at all times.

The single tape 130 requires a different means of controlling the pulley 131 than already described in connection with the continuous tape 80.

As before, the pulley 131 is mounted on a 60 shaft 133 rotatably mounted in bearings arranged at the free ends of arms 134 projecting from the machine frame 20. A segmental gear 135 is provided similar to the gear 93 already described and which meshes with a pinion 136 mounted for 65 rotation on the shaft 133. But instead of the pinion being connected directly to the pulley 131 to rotate same, it is connected to the pulley through a latching means which permits the pulley to be freed at times from the pinion.

70 This latching means consists of a radial arm 137 rigid with the pinion and carrying at its outer end a latch member 138 pivotally mounted thereon to swing out and in and yieldingly held inwardly by a tension spring 139 connected between the arm 137 and the latch 138.

A pin 140 projects out from one side of the pulley 131 and is adapted to be engaged by the latch 138 which is provided with a shoulder 141 for engaging the pin 140 and rotating the pulley counter-clockwise (see Fig. 8). The point 142 of the latch 138 is beveled or inclined on its inner side so that it can readily pass over and engage the pin 140. To free the latch from the pin 140 at the opposite end of its movement, a rigid stop pin 143 is provided, mounted on the adjacent 10 bracket arm 134 and over which the free end of the latch passes and by which it is lifted. As soon as the latch is lifted free of the pin 140, the tension device 132 to which the other end of the tape 130 is secured, pulls the tape back and rotates the pulley 131 in the opposite direction. 15

The latch is disengaged by the pin 143 just as the segmental gear 135 begins its return movement and the tension device 132 rotates the pulley backwards until the pin 140 in the 20 pulley again engages with the latch 138. A suitable stop pin 144 is arranged to limit the inward movement of the latch 141 when it is free of the pin 140.

The tape tension device 132 consists of a tape 25 drum 145 mounted for free rotation on a sleeve 146 carried by a shaft 147 which is held in brackets 148 on the machine top 21.

A spring 149 of the clock spring form is provided, mounted in a casing 150, and is connected 30 at its inner end with the drum 145 by a pin 151 fixed in the side of the drum and at its outer end to the inner periphery of the casing 150. The spring casing is mounted for rotation on the sleeve 146, and is held against rotation by 35 projections 152 on the outer periphery of the casing and which projections are adapted to be engaged by a spring pressed latch 153 pivotally mounted on a fixed bracket 154. The casing 150 is adapted to be rotated by hand to wind up the 40 spring 149 to put a tension on the tape 130 and is provided with rigid projections 155 for this purpose. The rotatable parts are held in place longitudinally on the sleeve 145 between a fixed collar 156 at one end and a removable collar 157 45 at the other end secured in place by a set screw.

It sometimes occurs upon the envelope ejecting movement of the tape 130, that it starts into motion so suddenly that it slips beneath the envelope and does not start the ejection of same 50 quickly enough. To avoid this possibility I arrange a non-skid abutment 158 adjustably mounted on one edge of the tape 130 and adapted to engage the envelope and cause it to move with the tape to be ejected. 55

This abutment 158, as best shown in Fig. 10, consists in a metal block 159 provided with a longitudinal slot 160 near its bottom to receive an edge of the tape. In the slot 160 and above the tape there is a pressure plate 161 which is held in place by vertical guide pins 162, projecting up through holes provided in the block 159. The pressure plate is clamped down upon the tape by a screw 163 mounted in the block 159. The forward end of the block is provided with an 60 upwardly inclined projection or tongue 164 adapted to project above the adjacent end of an envelope to be discharged and not let the envelope be disengaged from the abutment 158. 65

In practice the non-skid abutment 158 is adjusted to such a position on the conveyor tape 130 that it does not interfere with the positioning of the article to be printed, in printing position, against the regular registering stop 104. 70 75

but is positioned beyond same during the printing operation.

As the tape 130 is moved to the left to carry the printed article away from printing position and discharge same, the non-skid abutment is in position to engage the printed article, if necessary, and ensure its discharge movement with the tape.

As best shown in Fig. 5, this form of mechanism is provided with a yielding roll 165 similar to the roll 99 already described for holding the envelope down in printing position but in this instance instead of being located centrally over the tape 130, it is off-set side-wise to allow the abutment 158 to pass freely past same.

A third form of the invention is shown in Figs. 11 to 13, inclusive. In this form, instead of the feed tape as already described, there is provided a sliding metallic carrier which is moved back and forth somewhat similar to the described movements of the tapes.

In this form of the invention instead of deriving motion for the feeder through the shaft upon which the head 22 is mounted, motion is derived directly from the head, and the mechanism which takes the place of the feed tapes etc., herein before described, is as follows:

An envelope carrying slide device is provided which consists of two flat strap-like bars 166 which are arranged longitudinally of the machine top in position to receive the side edge portions of the envelopes to be printed. These bars 166 are parallel with each other and are secured at their inner ends to a cross bar 167. They are secured to the under sides of blocks 168 which are adjustably mounted on the cross bar 167 to be adjusted from and toward each other to accommodate envelopes of different widths. The cross bar 167 is secured to the inner end of a flat slide member 169 which is mounted to slide longitudinally of the machine in a fixed slide guide 170 secured upon the top 21 of the machine. Above the front slide bar 166 there is a second bar 171 adapted when the envelope is in printing position to lie down on the envelope and hold it flat down in place. This bar 171 is pivoted at its inner end to the adjacent block 168 to swing up and down and its free end 172 is bent or formed upwardly to engage and ride over the shaft 71 of the feeding mechanism and be lifted free of the envelope on the ejecting movement.

The slide guide 170 is provided with a longitudinally extending opening 173 on its under side and through which a post 174, rigid with the slide member 169, projects downwardly.

This post is connected by a horizontal link 175 with a long arm 176 of a bell-crank 177, which has a short arm 178 by which the bell-crank is adapted to be swung on its pivot 179. The pivot 179 is mounted in the free end of a flat projection 180 extending out from the side of the slide guide 170.

For swinging the bell-crank 177 back and forth and through the bell-crank moving the slide 169 back and forth, the free end of the short arm 178 of the bell-crank 177 is connected by a rod 181 with a projection 182 extending out rigidly from the side of the imprecision member 22 of the printing machine. As explained before, the member 22 has a forward and back rocking motion which moves the printing head up and down and this forward and back rocking motion is utilized to move the feed slide mechanism to carry the envelope into printing position and to

eject it from printing position. As the free end of the bell-crank arm 178 swings in a horizontal plane and the opposite end of the connecting rod 181 swings in a vertical plane, suitable universal joints 183 and 184 are used in connecting the rod 181 at its ends to the member 22, and to the bell-crank 177.

The full line position of the parts in Fig. 11 shows the limiting position on its ejection movement, and the dotted line position shows the extreme position of the feeding movement. As in the other forms, an adjustable stop 185 is provided for limiting the inward movement of the envelope to cause it to properly register with the printing mechanism. This stop is fixed on one end of a rod 186 which is adjustably mounted in a fixed bracket 187 secured to the rear end of the slide guide 170.

Otherwise than as described the feed mechanism including the feed rollers etc., are the same in this form of the invention as in those already described.

As many other modifications of the invention will readily suggest themselves to one skilled in the art I do not limit or confine the invention to the specific details of construction of the forms described, except within the scope of the appended claims.

I claim:

1. In a feed mechanism of the kind described for co-operation with a printing machine, a tape for moving the articles to be printed, into and out of printing position, a pulley to which one end of the tape is secured for moving the tape in one direction, a segmental gear and a co-operating pinion for intermittently rotating said pulley, and latch means for connecting the pinion to the pulley for rotating same.

2. The invention defined in claim 1, and means for unlatching the pinion from the pulley at one end of its movement, and means for automatically closing the latch at the opposite end of the movement.

3. In a mechanism of the kind described, a reciprocating tape for conveying articles to be printed to printing position, and an abutment on the tape arranged and adapted to engage the articles as the tape is operated to remove them from printing position.

4. The invention defined in claim 3, the abutment being adjustably mounted on the tape and arranged to be free of the article when same is in printing position.

5. The invention as defined in claim 3, stop means for accurately positioning the article in printing position, the abutment on the tape arranged to be positioned beyond the said stop means when the article is in printing position.

6. In a blank feeding mechanism of the kind described for co-operation with a printing machine, a reciprocating tape arranged and adapted to carry an article, such as an envelope into a position to be printed, and after it has been printed to withdraw it from the printing position, the envelope remaining in substantially, relatively fixed contact with the tape during this operation, a power operated member to which one end of the tape is secured for moving the tape in one direction, and a yielding tension device to which the other end of the tape is secured for moving the tape in the opposite direction.

7. In a mechanism of the kind described for co-operation with a printing machine having a printing position, a reciprocating flat slide member arranged and adapted to carry an article

such as an envelope, into a position to be printed, and after it is printed to withdraw it from printing position, the arrangement being such that the article is in substantially relatively fixed contact with the flat slide member during this operation, means connecting the slide member with the printing machine for movement thereby, and an elongated member pivotally mounted on the slide member adapted to rest upon the upper surface of the article being printed and hold it in contact with the flat slide member.

5. The invention as defined in claim 7, and means for automatically lifting the elongated member as the slide member is moved to discharge the article.

8. The invention as defined in claim 7, and means for automatically lifting the elongated member as the slide member is moved to discharge the article.

9. In a blank feeding mechanism of the kind described for co-operation with a printing machine having a printing position a flat reciprocating member operatively connected to the printing machine for movement thereby and arranged to carry a blank such as an envelope, into said printing position to be printed, and after it is printed to carry it away from the printing position, the article being in substantially relatively fixed contact with the flat reciprocating member throughout this operation, and a pressure member arranged adjacent to said printing position above said reciprocating member arranged and adapted to press the article against the said reciprocating member as and for the purpose specified.

10. In a blank feeding mechanism of the kind described, for co-operation with a printing machine having a printing position, a holder for articles to be printed, means for successively separating and advancing articles from the holder to said printing position and including an intermittently operated blank separating member, a pair of advancing rolls, a flat reciprocating member arranged and adapted to receive the blank from said pair of advancing rolls and advance it to printing position, the arrangement being such that the article lies in substantially relatively fixed contact with said flat reciprocating member during this operation, means co-operating with the reciprocating member arranged and adapted to hold the blank down upon the reciprocating member during the blank advancing and blank ejecting movements thereof.

11. The invention as defined in claim 9, the flat, reciprocating member comprising a flat metallic member.

12. The invention as defined in claim 9, the flat reciprocating member comprising a pair of parallel flat metallic strips.

13. The invention as defined in claim 10, the flat reciprocating member comprising a flat metallic member.

14. The invention as defined in claim 10, the flat reciprocating member comprising a pair of parallel flat metallic strips.

WM. WARD DAVIDSON.
